UNITED STATES PATENT OFFICE.

GEORGE W. MOORE, OF SPRINGFIELD, MISSOURI.

VALVE-TESTING APPARATUS.

1,181,029.

Specification of Letters Patent. Patented Apr. 25, 1916.

Application filed September 3, 1915. Serial No. 48,859.

To all whom it may concern:

Be it known that I, GEORGE W. MOORE, a citizen of the United States, residing at Springfield, in the county of Greene and State of Missouri, have invented new and useful Improvements in Valve-Testing Apparatus, of which the following is a specification:

This invention relates to apparatus for testing safety valves, and has particular reference to devices primarily adapted for testing valves of tank cars.

An object of the invention is to provide a simple, cheap and efficient apparatus whereon the valves may be tested and regulated in a simple, cheap and expeditious manner.

With the above and other objects in view, the improvement resides in the construction, combination and arrangement of parts set forth in the following specification and falling within the scope of the appended claims.

In the drawing: Figure 1 is a top plan view of the door of an ordinary tank car illustrating the application of my improvement, and Fig. 2 is an elevation of the improvement, parts being broken away and parts being shown in section.

In tank cars safety valves must be tested and adjusted within stated periods, and a record of such tests must be stenciled upon the elbow which is arranged between the valves and the tank dome. Heretofore such tests are usually made of compressed air or water. As all tank cars are of eight to ten thousand gallon capacity, air or water consumed as well as time and labor expended in the making of such tests will be apparent. As such tests cannot be made when the car is under load, it is not infrequent that cars have been set back because the proper tests of the valve was not made before the said car started on its journey. In the latter instance it is necessary to transfer the contents of the car to another car which has had its valves properly tested, and thus it will be noted that quite an amount of time and labor is consumed in transferring of the load as well as in running the car to and from the transfer point.

It may therefore be considered the primary object of my invention to provide means or apparatus whereby the valves of the tank cars may be properly tested either when the car is empty or under load. I accomplish this object by the apparatus disclosed in the accompanying drawings, and

in the said drawings the numeral 1 designates the dome of an ordinary tank car, which in the present instance has its man-hole 2 shown as open. The safety valves, two in number, are indicated by the numerals 3, the same being provided with an elbow 4 which communicates with the tank dome 1. The valves 3 are provided with regulating nuts 5.

With my improvement I provide an apparatus which may be readily inserted through the man hole 2 into the dome 1, the same including a plurality of removable elements and including a head member 6 having its open mouth provided with a gasket 7 which is adapted to be compressed against the mouth of the valved elbow in the dome 1. The hollow head 6 has threadedly and centrally connected therewith a pipe section 8, which in turn is threadedly secured to one of the arms of a cross coupling 9. This coupling, through the medium of pipes and bushings has connected thereto a pressure gage 10, and the arm of the cross diametrically opposite that provided with the pipe 8 is closed by the threaded end of a rod 11. The outer end of this rod is reduced and is also threaded, as at 12, and receives a threaded bore at one end of a turnbuckle 13. The threaded bore at the opposite end of the turnbuckle, which, it should be stated, has its threads arranged at a different angle or pitch from the threads receiving the end 12 of the rod 11, has screwed therein the threaded end 14 of a rod 15, the said rod having its free end pointed, as at 16. Communicating with the arm of the cross diametrically opposite that to which the pressure gage 10 is connected is a casing 17 of an angle cock, the same being provided with an operating handle 18, and an elbow coupling 19 connects the said cock with an air hose coupler 20.

The operation of the device may be briefly described as follows: The gasket 7 of the head 6 is, as previously stated, arranged at the elbow of the valves 3. The turnbuckle is adjusted so that the pointed end 16 of the rod 15 will contact with the inner face of the dome diametrically opposite the said head 6. An air pipe is connected with the air hose coupler 13, and sufficient air is permitted to enter the pipe sections of the device to revolve the hand of the gage until the same has indicated a desired pressure, say twelve pounds. The nuts 5 of the valves

3 are then adjusted so that the said valves will blow off under a twelve pound pressure. After this is accomplished the device is removed through the manhole 2 of the dome, 6 and the entire time, from actual test, required in properly adjusting the valves to the desired amount of pressure will not require more than fifteen minutes, so it will be noted that the cost of such test is greatly 10 reduced.

Having thus described the invention, what I claim is:

1. In an apparatus for testing the safety valves upon the domes of tank cars, a cross, 15 longitudinally adjustable rods connected with the cross and closing one of the arms thereof, a pipe section arranged diametrically opposite the rods, a hollow head for

the pipe section, a gasket for the hollow head, a gage connected with the cross, a cock 20 connected with the cross, and an air hose coupler connected with the cock.

2. An apparatus for testing safety valves upon domes of tank cars comprising a hollow head having a compressible gasket 25 therein, a pipe connected with the hollow head, an air gage for the pipe, a valve air inlet for the pipe, and a longitudinally adjustable rod member extending from and disposed in a line with the pipe. 30

In testimony whereof I affix my signature in presence of two witnesses.

GEORGE W. MOORE.
